CLAIM

The ornamental design for a patient transfer device, as
shown and described.

DESCRIPTION

FIG. 1 is a bottom perspective view of a patient transfer
device showing our new design;

FIG. 2 is a top perspective view thereof;

FIG. 3 is a top plan view thereof;

FIG. 4 is a side elevational view thereof; and

FIG. 5 is a cross sectional view thereof, taken along the
line 5—5 of FIG. 3.
